UNITED STATES PATENT OFFICE

2,228,439

WINDOW OPERATOR

George Cerny, St. Louis, Mo., assignor to Pauly
Jail Building Company, St. Louis, Mo., a cor-
poration of Missouri

Application September 21, 1939, Serial No. 295,902

10 Claims. (Cl. 268—21)

This invention relates to window operators; and has special reference to windows including a vertical series of sections supported for swinging movements on horizontal axes from and to closed and open positions.

Objects of the invention are to provide an improved window including a vertical series of sections supported by pivots extending from their ends through the vertical portions of the window frame, a vertically movable rack bar in each side member of the frame for rotating said pivots and thereby opening or closing the respective window sections; to provide novel metallic sash structure for the window panes including metallic frame members shaped and formed to maintain necessary and desired rigidity indefinitely; to provide sealing weatherstrip devices for maintaining sealed joints between the respective sections and also between the sections and the window frame; to provide connections operated by said rack bars for turning the pivots of the window sections to open and to close said sections; and to provide novel easily operated mechanism for moving said rack bars vertically as required to open the window sections successively and to close them in the same order.

Another object of the invention is to provide improved operating mechanism for the window sections comprising levers connected with the pivots by which the sections are supported, vertically movable bars having racks thereon for engaging gear segments respectively and at different vertical positions of the rack bars in order to operate said levers and move the window sections, and means for sealing in weatherproof manner the respective window sections when they are closed.

Other objects will appear from the following description, reference being made to the annexed drawings, in which—

Fig. 1 is an inner side elevation of a window constructed in accordance with the present invention.

Fig. 2 is a side elevation of the window frame and sash-operating mechanism looking in the direction of the arrows on the line 2—2 of Fig. 1, showing the parts in the positions they occupy when all of the window sections are closed.

Fig. 3 is a similar view showing the upper and lower window sections open.

Fig. 4 is a similar view showing all but one of the window sections open.

Fig. 5 is an enlarged view of one of the gear

segments forming a part of the operating mechanism for each window section.

Fig. 6 is a side elevation of one of the cooperating lever members for moving the window sections.

Fig. 7 is an enlarged vertical sectional view on the line 7—7 of Fig. 1, parts being omitted.

Fig. 8 is an enlarged horizontal sectional view on the line 8—8 of Fig. 1.

Fig. 9 is an enlarged horizontal sectional view on the line 9—9 of Fig. 1.

Fig. 10 is an enlarged sectional view on the line 10—10 of Fig. 2, showing more clearly the connections for moving the window sections.

The window frame is mounted rigidly in the proper opening in the building wall, and may include duplicate vertical side portions each composed of angular members 1, 2, and 3, attached together and to the building wall at the sides of the window opening, and having their upper ends attached to the rigid frame device 4 and their lower ends attached to the rigid frame device 5. A frame thus constructed provides vertical spaces 6 in the vertical side portions and a space 7 in the lower portion thereof. The operating mechanism for the window sections is mounted in these spaces and thereby concealed and protected. A vertical reinforcing bar 8 is attached to each vertical angular member 1. The frame further comprises angle bars 9 attached to the members 1, the top member 4 and the bottom member 5. Angle bars 10 (Fig. 8) are attached to the angle bars 9 at the sides of the frame, and channel members 11 (Fig. 7) are attached to the angle bars 9 along the top and bottom of the frame.

Resilient metallic sealing strips 12 are secured between the inwardly extended portions of the angle bars 9 and 10 at the sides of the frame, and have angularly extended arms 13 engaging the reinforcing bars 8. Resilient sealing weatherstrips 14 are attached between the angle bars 9 and 11 at the top and bottom of the frame and extend outwardly therefrom for cooperation with the respective window sashes.

Each end of the respective window sections comprises a metallic strip bent to provide a supporting portion 15, an outwardly extended pane abutting portion 16, and a laterally extended flange 17 contacting the adjacent member 1. The lower ends of the end members of each window section are connected by a metallic strip bent to provide a portion 18, an outwardly extended pane abutting portion 19, and a down-

wardly extended margin 20. The upper ends of the end members of each window section are connected by a metallic strip bent to provide an upper portion 21, an inwardly extended abutting frame portion 22, and a downwardly extended flange 23 at the outer margin of the portion 21. A reinforcing bar 24 may be mounted in the frame 22 wherever needed to prevent downward bending of the window sash. In instances where it is desired to divide the longitudinal area of any window sash to receive separate panes of window glass, T-bars 25 may be attached to the lower and upper horizontal portions of the respective window sashes (Figs. 1 and 9). The window panes 26 are mounted in the respective window sashes against the abutments 16, 19 and 22 and secured in position by putty 27, or otherwise as desired. The upper portion 21 of each window sash, excepting the uppermost window sash, has attached thereto an angle strip 28 constituting an abutment for the next adjacent window sash portion 18, while the flanges 20 of the respective window sashes engage the outer edges of the next lower window sashes when the window sashes are closed, as shown in Fig. 7. Resilient sealing weatherstrips 29 are attached to the angle members 28 for close contact with the lower edges of the adjacent window sashes when the windows are closed. These resilient weatherstrips 29 are in continuation of and in cooperative relationship with the strips 12 and 14. The upper portion of the window frame includes an angle strip 30 cooperating with and extending downwardly beyond the top of the upper window sash at the outside to constitute a guard and protecting device, preventing the passage of water and other substances inwardly above the upper window sash. A bar 31 is attached to the lower frame device 5, has an abutment for the downwardly extended flange 20 of the lower window sash, and cooperates therewith to prevent inward passage of rain and other substances.

Each window sash is pivotally supported by a pair of axially aligned pivots 32 attached to the ends thereof and extending through bearing sleeves 33 attached to and extending through the reinforcing bars 8 and the members 1 into the spaces 6. Levers 34 are rigidly attached to the outer ends of the pivots 32 within the spaces 6, and have slots 35 receiving rollers 36 rotatively supported by levers 37 supported for turning movements on pivots 38 attached to the members 42 within the spaces 6 (Figs. 2 and 10). The levers 37 are attached by welding or otherwise to gear segments 39, also supported for turning movements on the pivots 38. By this construction and arrangement, the levers 37 will move the levers 34 when said levers 37 are operated from the positions shown in Fig. 2 to the positions shown in Figs. 3 and 4 and beyond, and vice versa.

A vertically movable rack bar 40 is mounted for vertical sliding movements in each vertical space 6 which are at the sides of the window frame. Each of said rack bars 40 is formed with a series of spaced racks 41 corresponding to the respective segments 39 and adapted to be moved successively into and out of meshing engagement therewith. The order in which the racks 41 may be engaged with and disengaged from the respective segments 39 may be varied as desired, so that the different window sections may be opened successively in any desired order and closed in the reverse order. These rack bars are

mounted between and are guided by the levers 37 and guide elements 42 which are secured to the members 1 by fasteners 43 (Fig. 8). The lower ends of the rack bars operate between guides 44 and 45 attached to the members 1 substantially below the lower pivots 32 (Figs. 2 and 4).

In each space 6 a sprocket chain 46 has its ends engaged with the rack bar 40 and is engaged over upper sprocket wheels 47 and lower sprocket wheels 48. The lower sprocket wheels 48 are attached to the ends of a horizontal shaft 49 rotatively supported within the lower space 7. A worm gear 50 is attached to the shaft 49 and is in permanent engagement with a worm 51 rigid on a short shaft 52 so that, when said shaft 52 is rotated, the chains 46 will be operated and the rack bars 40 moved vertically. A crank 53 is attached to the inner end of the shaft 52 so that said shaft may be operated manually as required to open and close the window sections.

As shown, the upper racks 41 will first engage the upper segments 39 and thereby open the upper window section. Next, the lower racks 41 will engage the lower segments 39 and thereby open the lower window section, the upper racks 41 passing out of engagement with the upper segments 39 at the time the upper window section is in open position. At the time the lower window section is in open position, the lower racks 41 pass out of engagement with the lower segments 39. Thus, it is apparent that only the upper window section may be opened and kept open while the remaining window sections remain closed, or both the upper and lower window sections may be opened and kept open while the intermediate window sections remain closed. Or, as shown in Fig. 4, the intermediate window sections may be successively opened and kept open by continued upward movement of the rack bars 40.

When it is desired to close any or all of the window sections, the rack bars 40 are moved in the reverse direction to the extent required to close the selected window sections in the reverse order to that in which they were opened.

It is now apparent that this invention attains all of its intended objects and purposes efficiently and satisfactorily; that the window frames, sashes and operating mechanism are of strong and durable construction and may be varied widely within the scope of equivalent limits without departure from the principle of the invention.

I claim:

1. A window comprising a frame, a window sash mounted in said frame, pivots at the ends of said sash supporting the same in said frame for swinging movements to open position and to closed position, levers attached to said pivots, gear segments operatively connected with said levers, pivots supporting said segments for turning movements, vertically movable rack bars for operating said segments and thereby said levers to move said sash to open position and to closed position, and mechanism supported by said frame for operating said rack bars.

2. A window comprising a frame, a window sash mounted in said frame, pivots attached to said sash and supported by said frame for turning movements, levers attached to said pivots, rack segments in said frame beyond the ends of said sash, levers attached to said rack segments and engaging said first named levers for operating the same when said rack segments are turned, means supporting said rack segments for turning

movements, vertically movable rack bars in said frame for engaging and turning said rack segments to move said window sash to open position and to closed position, mechanism enclosed by 5 said frame for operating said rack bars, and manual means for operating said operating mechanism.

3. A window comprising a metallic frame having vertical spaces in its side portions, a metallic 10 window sash mounted in said frame, pivots attached to the ends of said sash and extending through said frame into said spaces, levers attached to said pivots in said spaces, rigid supports in said spaces spaced from said pivots, gear segments mounted for turning movements on said supports, means for operating said levers by said 15 segments, vertically movable bars mounted in said spaces, racks rigid with said bars for engaging and operating said segments, means for 20 guiding said bars, a horizontal shaft mounted in the lower portion of said frame below said sash, means for rotating said shaft, and connections operated by said shaft for moving said bars vertically to turn said segments and thereby operate 25 said window sash.

4. A window comprising a frame, a vertical series of window sashes mounted in said frame, pivots at the ends of said respective window sashes supporting the same in said frame for 30 swinging movements to open positions and to closed positions, levers attached to said pivots, gear segments operatively connected with said levers respectively, means for supporting said segments for turning movements, vertically movable bars in said frame beyond the ends of said sashes, racks on said bars for engaging and operating said segments to move said sashes to open 35 positions and to closed positions, and mechanism supported by said frame for operating said bars.

40 5. A window comprising a frame having vertical spaces in the sides thereof, a vertical series of window sashes mounted in said frame, pivots attached to the ends of said respective window sashes and extending through the sides of said 45 frame into said spaces and supporting said sashes for swinging movements to open positions and to closed positions, levers attached to said pivots, gear segments supported for turning movements in said spaces, means for operating said levers by said gear segments, vertically movable bars mounted in said spaces, spaced racks rigid with said bars for movement into and out of engagement with said gear segments successively to operate said levers and move said sashes to open 50 positions in successive order, and mechanism supported by said frame for operating said bars.

60 6. A window comprising a frame, a window sash mounted in said frame, pivots at the ends of said sash supporting the same in said frame for swinging movements to open position and to closed position, gear segments for turning said pivots to move said sash to open and to closed positions, rack bars mounted in the sides of said frame for engaging and operating said gear segments to move said sash as aforesaid, upper and 65 lower sprocket wheels rotatively supported in the sides of said frame, sprocket chains engaging said sprocket wheels and having their ends attached

to said rack bars between said sprocket wheels, and manual mechanism for rotating said lower sprocket wheels and thereby moving said chains to move said rack bars vertically to open and to close said window sash. 5

7. A window comprising a frame, a vertical series of window sashes mounted in said frame, pivots at the ends of said window sashes supporting the same in said frame for swinging movements to open positions and to closed positions, 10 levers attached to said pivots for moving said sashes to open and to closed positions, connections for operating said levers to move said sashes as aforesaid, vertically movable bars in the sides of said frame for engaging said connections successively and operating said connections successively to open said window sashes successively, sprocket chains movably supported in the sides of said frame and having their ends attached to said bars, gearing for operating said sprocket 15 chains in one direction to move said bars upwardly and in the opposite direction to move said bars downwardly, and manual means for operating said gearing. 20

8. A window comprising a frame, a sash 25 mounted in said frame, pivots supporting said sash for swinging movements to inclined open position and to closed position, levers attached to said pivots in said frame and having slots therein, levers pivotally supported in said frame, 30 parts supported by said second levers engaging in said slots for operating said first levers by said second levers to move said sash to open and to closed positions, gear segments attached to said second levers, racks supported in said frame, 35 mechanism for moving said racks to operate said gear segments and thereby said levers to open and to close said window sash. 40

9. A window comprising a frame, a series of window sashes pivotally mounted in said frame, 40 connections for moving said window sashes to open position and to closed position, rack bars in said frame for engaging and operating said connections successively to open and to closed positions, sprocket 45 chains attached to said rack bars for moving said rack bars in one direction to open said window sashes and in the opposite direction to close said window sashes, sprocket wheels engaging said chains, gearing for operating certain of said 50 sprocket wheels, and manual means for operating said gearing. 50

10. A window comprising a frame, a window sash mounted in said frame, pivots supporting said window sash for swinging movements to open position and to closed position, levers attached to said pivots for turning the same, gear segments rotatively supported in said frame, rack bars for operating said gear segments, means for guiding said rack bars in longitudinal movements, lever devices connected with said gear segments, means for operating said levers by said lever devices to swing said window sash to different adjusted positions and hold the same in said positions, and manual mechanism for operating said 60 rack bars. 65

GEORGE CERNY.
